UNITED STATES PATENT OFFICE.

ISRAEL W. MARSHALL, OF YORKLYN, DELAWARE, ASSIGNOR OF ONE-HALF TO THOMAS E. MARSHALL, OF YORKLYN, DELAWARE.

SHEET-COMBINING MACHINE.

No. 897,757.

Specification of Letters Patent.

Patented Sept. 1, 1908.

Application filed October 8, 1907. Serial No. 396,403.

To all whom it may concern:

Be it known that I, ISRAEL W. MARSHALL, a citizen of the United States, residing at Yorklyn, in the county of Newcastle and 5 State of Delaware, have invented certain new and useful Improvements in Sheet-Combining Machines, of which the following is a specification.

This invention relates to improvements in 10 machines used in the manufacture of indurated fiber and particularly to that class in which any number of separately fabricated sheets are combined, indissolubly into one.

The objects are:—To provide a machine 15 adapted to operate on a plurality of rolled sheets, unrolling, completely submerging and saturating each sheet from both sides, within a tank, said submerging device having novel means whereby it may be raised or lowered with reference to the tank, and devices combined with the machine whereby 20 the several sheets are pressed and caused to coalesce, in the presence of heat, into a single continuous unit.

25 A further object is the conservation of the impregnating solution used in the tank and means for the convenient inspection, removal or insertion of the sheets in their course through the machine.

30 These and other objects are attained by the novel combination and arrangement of parts in the mechanism hereinafter fully described and shown in the accompanying drawings, forming part of these specifications and in which have been used similar characters on similar parts.

Figure 1, is a side elevation of the complete machine. Fig. 2, is a plan view of the same. Fig. 3, is a perspective view of the 40 tank submerging rolls. Fig. 4, is a detail of the scraping device. Fig. 5, is a side elevation of the steam appliance, and Fig. 6, is a front elevation of the same.

The machine comprises a substantial 45 frame 1, supported by suitable pedestals 2, resting on a firm foundation; the rolls of paper, made of vegetable fiber and of an open, porous texture, are provided with shafts 3, the ends of which rest in open bearings 50 formed at the upper surface of the roll frame 4, which may be an integral part of the frame 1, or detached from it as preferred.

While three rolls are shown on the frames it is understood that a greater or lesser num-

ber may be similarly positioned, according to 55 the thickness of the finished product required; each of the several rolls are provided with a friction device 5, acting as a drag or brake to prevent the too rapid unwinding of the sheets and keep the same under a moderate 60 tension as they are unrolled in their passage over the roller 6, common to all the sheets, and which is allowed to revolve freely in its bearings 7. From the roller 6, the sheets are separated, each passing over individual rollers 65 8, mounted in bearings 9, so formed that the said rollers are readily removable therefrom, through open angular slots in the plate 10, containing the bearings, and which form the upper part of the stand 11, attaching at its 70 base to the frame 1.

The tank 12, secured between the sides of the frame, is preferably constructed of copper or other material non-corrodible by the liquids contained within; it is made slightly 75 wider than the sheets to be immersed, with a curved front and provided with a suitable draw off valve, as at 13. Mounted on its reinforced upper side edges are bearings 14 and 14', and 15 and 15', in the first of which are 80 pivoted levers 16 and 16', having their lower ends pivotally connected with the roll holding frames 17 and 17', said levers 16 and 16', being of an appropriate length to swing freely within the tank 12 and clear the front 85 end which is curved to a corresponding radius.

Levers 18 and 18', are pivoted at the rear bearings 15 and 15', and are similarly connected to the rear of the roll holding frames 90 17, which said frames carry the rollers 19, so mounted as to be freely revoluble and arranged in parallel pairs in such manner that sheets from the individual rollers 8, are kept 95 separate from each other and from contact with the walls of the tank in their passage through the liquid therein, on the rollers 19.

Straight extensions 20 and 20', of the levers 18 and 18', have attached, at their upper ends, the chains 21 and 21', the same being wound on the shaft 22, contained in bearings 23 and 23', attached to the frame 1, at the rear of the tank; the shaft 22, is provided with the hand-wheel 24, for operating and also the ratchet wheel 25, and pawl catch 26, 100 to hold the shaft against revolution when the levers are raised from the tank; the foregoing mechanism obviously being capable of ac- 105

complishing this purpose and that of raising the rollers above and parallel to the tank at such times as may be desirable.

The front bearings 14 and 14', are extended upward and towards the front, as at 27 and 27', to provide seats for square scrapers 28 and 29, removably connected but non-rotatable, their purpose being to remove the excess liquid from the lower and upper sheets, as they pass between them from the rolls 19, such excess being returned to the tank below. From the scrapers the sheets, now in contact with each other, pass circuitously over the cylinder 30, between it and the lower fixed cylinder 31, which it is caused to partially surround, being delivered from the lower side to subsequent operations, not a part of this invention.

The cylinder 30, is provided with stub shafts set in its ends, revolving in bearings 32 and 32', slidably connected to guides on the angular upper portion of the frame 33; on the top of these bearings are eyes in which are secured chains 34 and 34', attached to the shaft 35, in such manner as to be wound thereon when the shaft is revolved, which it may be by reason of the gear wheel 36, secured on it beyond the bearings 37 and 37', which are rigidly affixed to the extreme upper ends of the frame members 33. Motion is communicated to the worm gear wheel 36, by the worm 38, on the shaft 39, the latter being disposed parallel to the guides on the frame 33, to which it is secured by suitable bearings, and is provided at its lower end with a hand wheel 40, arranged convenient for operation at such times as it may be desired to raise the cylinder 30.

The lower and larger cylinder 31, is provided with flanges 31', at both ends for the purpose of guiding the sheet properly; also with similar stub shafts at its ends, the same revolving in fixed bearings 41 and 41', the lower part of which is integral with the frames 33, which are securely attached to the main frame members 1. Beyond the bearing 41', on the extending end of the shaft from the cylinder 31, is affixed a spur gear 42, driven by the pinion 43, on a counter shaft—not shown—when the machine is in operation; the upper cylinder 30, is driven by frictional contact with the lower cylinder, or the interposed sheet, only. This extended shaft is hollow and is connected with a suitable stuffing box 44, in the steam case 45, having a pipe 46, from a supply source of steam, whereby a temperature of approximately 90 degrees Fahrenheit may be obtained in the cylinder 31. The upper cylinder 30, has a similar hollow shaft extending through the bearings 32', and connected in like manner with a stuffing box 46, in the steam case 47, which passes through a packed sleeve 48,—thus allowing the cylinder to be raised,—connecting with a steam

supply source as at 49, from which may be obtained a temperature of approximately 180 degrees, or 90 degrees greater than that of the lower cylinder, as it is found preferably to thus arrange the relative proportion of heat in said cylinders as indicated.

While any liquid may be contained in the tank 12, and the machine used for divers purposes, in the manufacture of indurated fiber, I prefer to use a solution of zinc chloride, as the same has a certain affinity for vegetable fibers, causing them to partially gelatinize and combine under the application of heat and pressure for the cylinders.

Obviously I may modify the details somewhat without departing from the general spirit of the invention, hence do not wish to be understood as limiting the construction to the exact arrangement indicated.

Having thus described my invention, what I claim as new and desire to secure by Letters Patent is:

1. In a sheet combining machine the combination with a pair of heating cylinders arranged one above the other, of means for directing partially gelatinized sheets of paper between said cylinders, and means for driving the lower cylinder whereby the sheets of paper will be combined as they pass between the cylinders.

2. In a sheet combining machine the combination with a pair of revoluble heating cylinders arranged one above the other, of means for directing partially gelatinized sheets of paper between said cylinders, means for raising the upper cylinder and means for driving the lower cylinder, whereby the upper cylinder will be driven by frictional contact with the interposed sheets.

3. In a machine of the class described, the combination with a frame and tank, levers pivotally mounted on said tank, carrying a roll holding frame, scrapers arranged in advance of said tank, revoluble heating cylinders arranged at the front of the machine, and means for swinging said roll holding frame.

4. In a machine of the class described, the combination with a tank, drying and pressing cylinders, of a roll holding frame pivotally mounted in said tank, means for directing sheets of paper to said rolls in said tank, and from said rolls to said drying and pressing cylinders, and means for swinging said roll holding frame.

5. In a machine of the class described, the combination with a tank provided with bearings on its upper side edges, adjacent each end, of levers pivotally mounted in said bearings, a roll holding frame carried by said levers, and means for operating one pair of levers.

6. In a machine of the class described, the combination with a tank, of bearings secured on its upper side edges, one pair of

bearings extending upwardly and forwardly forming seats, square scrapers arranged in said seats, levers pivotally mounted in said bearings carrying a roll holding frame, means for directing sheets of paper through said tank over said rolls and scrapers, and means for swinging said roll holding frame.

In testimony whereof I have signed my name to this specification in the presence of 10 two subscribing witnesses.

ISRAEL W. MARSHALL.
